CLIP FOR TYPEWRITER RIBBON SPOOLS

Robert W. Weller, P.O. Box 398, Lomita, Calif. 90717

Filed May 19, 1969, Ser. No. 17,208

Term of patent 14 years

Int. Cl. D8—03

U.S. Cl. D8—259

FIG. 1

FIG. 2

FIG. 4

FIG. 3

FIG. 1 is a perspective view of a clip for typewriter ribbon spools, showing my new design.

FIG. 2 is a top plan view thereof;

FIG. 3 is a side elevational view as taken from the bottom side of FIG. 1; and

FIG. 4 is an end elevational view as taken from the left hand side of FIG. 1.

The broken line representation of ribbon spools is for illustrative purposes only.

I claim:

The ornamental design for a clip for typewriter ribbon spools, as shown and described.
